SAFETY MECHANISM

Jacob Hoffman, Chicago, Ill., assignor of one-half to Willy Dumke, Chicago, Ill.

Application November 16, 1934, Serial No. 753,321

17 Claims. (Cl. 192—131)

This invention relates to safety mechanism for punch presses or the like, and more particularly relates to mechanism of this character adapted to occupy both of the operator's hands while the press is in operation.

Punch presses of the type to which the present invention is particularly applicable embody a movable part in the form of a reciprocating ram suitably supported for operating upon a work piece at rest upon a rigid platform or bolster plate. The ram is usually power driven through the medium of a prime mover and is intermittently operated by suitable clutch mechanism controlled by a foot treadle. In general the work piece is placed under the ram by hand, and the finished piece is removed in the same manner. Should the operator engage the clutch too soon, or attempt to rearrange the position of the work piece during the interval between engagement of the clutch and the impact of the ram, his hand may be caught and severely injured if not amputated. Such accidents are, as a matter of fact, of all too frequent occurrence in the operation of punch presses and result not only in injury or loss of limb to the operator but also in serious economic loss to the employer.

It is an object of the present invention, therefore, to provide safety mechanism for punch presses which will require the operator to employ both hands for operating the press and which will otherwise instantly act to halt movement of the ram whereby the operator cannot have either hand in such a position as to be caught under the ram at the impact thereof.

Another object is to provide mechanism for halting the movement of the impact member of the machine a predetermined distance from the impact point and embodying manually operable control means requiring the simultaneous use of both of the operator's hands to release the impact member for further operation, the speed of the impact member being calculated to carry it from the halting point to the impact point before the operator can place his hands into the operative path of the impact member after releasing the same.

Another object is to provide a safety device of the foregoing character which may be installed easily and without rearranging the parts or changing the mode of operation of a press already set up for operation.

Another object is to provide a safety device operable as an auxiliary to the regular control means of the press to prevent operation of the

ram until the operator manually releases a safety by the use of both his hands.

Another object of the invention is to provide a safety device of the foregoing character having a pair of spaced manual control means arranged to remain inoperative except when the operator uses both of his hands simultaneously to operate the same. 5

Another object is to provide a safety device of the foregoing character which is adjustable to 10 vary the point at which the descending ram will be halted in spaced relation to the bolster plate.

Another object is to provide a safety device embodying shock absorbing means and adapted to lock the mechanism against further operation 15 should the usual drag brake be improperly adjusted so that the apparatus is not conditioned properly to halt substantially instantaneously when the safety device is active.

Another object is to provide a safety device of 20 the foregoing character embodying means operable to permit continuous operation of the press when desired.

Another object of the invention is to provide an apparatus of this character which is simple 25 in design; economical to manufacture and maintain while being simple and positive in action; practical and efficient in operation, and in general to produce an economical and efficient apparatus of the character referred to. 30

Other objects and advantages will become apparent in the following description and from the accompanying drawings, in which:

Figure 1 is a fragmentary side elevation of the head of a press embodying the principles of the 35 invention.

Fig. 2 is a front elevation of the press.

Fig. 3 is a fragmentary sectional view on an enlarged scale showing details of the latch mechanism of the safety device. 40

Fig. 4 is a fragmentary sectional elevation taken on line 4—4 of Fig. 3.

Fig. 5 is a fragmentary sectional elevation taken substantially along line 5—5 of Fig. 2.

Fig. 6 is an enlarged perspective view of the 45 latch forming part of the safety device.

Fig. 7 is an enlarged perspective view of the reciprocable clutch bolt.

Fig. 8 is a fragmentary sectional view showing the position of parts when the safety latch is in 50 locking relationship with the bolt.

Fig. 9 is a view taken along line 9—9 of Fig. 8.

Fig. 10 is an enlarged cross sectional view through the clutch bolt showing it in one operative position taken along line 10—10 of Fig. 5. 55

Figs. 11 and 12 are front end side elevational views, respectively, of a modified form of the invention adapting the press for continuous operation.

5 While the invention is susceptible of various modifications and alternative constructions, I have shown in the drawings and will herein describe in detail, the preferred embodiment, but it is to be understood that I do not thereby 10 intend to limit the invention to the specific form disclosed, but intend to cover all modifications and alternative constructions falling within the spirit and scope of the invention as expressed in the appended claims.

15 A safety mechanism according to the present invention may be built into the press during the course of its manufacture or it may be fashioned in the form of an auxiliary attachment to be incorporated in an existing machine. In either 20 instance, the relationship of parts is such as to make the safety mechanism a part of the control mechanism of the press, and the nature of the mechanism is such that the operator will be required to employ both hands to effect operation 25 of the machine.

As a matter of convenience, the invention is herein illustrated as being embodied in a conventional punch press including a stand or base 15 supporting a standard 17. A work support 30 such as a bolster plate 18 is disposed in the customary manner for receiving the stationary die and the work piece, while the usual movable impact member in the form of a reciprocable ram 19 is slidably mounted in the upper part of the 35 standard for operating upon the work supported by the bolster plate. Actuation of the ram 19 through a predetermined cycle of operation is effected through a suitably journaled crank shaft 20. Power from any suitable source continuously 40 drives at the desired speed a prime mover such as a fly-wheel 22 which is freely rotatable on one end of the crank shaft. Intermediary means such as a manipulable clutch mechanism 23 provides an operative connection of the crank shaft with the 45 prime mover for actuating the ram.

The clutch mechanism 23 is herein shown as of a type embodying a clutch wheel 24 of substantial thickness suitably secured fast upon the shaft 26 coaxial with and in juxtaposition to the fly-wheel 22. Adjacent the periphery of the clutch wheel is a clutch bolt well 25 herein shown as angular in form to receive a similarly shaped reciprocable pin or bolt 27. Near its hub, the fly-wheel 22 is provided with a plurality of shallow 50 apertures 28 of substantially the same transverse dimensions as the well 25 and adapted to be brought successively into alignment with the well by rotation of the fly-wheel. A bore 29 is formed in the inner end of the bolt 27 to receive a coil 55 spring 30 which is seated at its outer end about a stud 32 in the inner wall of the well 25. This spring is of a tension adapted normally to urge the bolt out of the well. It will thus be observed that the outer end of the bolt 27 will be forced 60 by the spring against the adjacent face of the fly-wheel 22 and when one of the apertures 28 is brought into coincidence with the wheel 25, the bolt will instantly engage in the aperture. Thus, the clutch wheel will be caused to follow the fly-wheel and thereby rotate the shaft 20, which in turn will cause the ram 19 to reciprocate.

In a usual arrangement, the means for controlling operation of the clutch takes the form of a weighted or spring loaded foot treadle 33 65 operative upon being depressed to move a rod

34 which in turn is pivotally connected at its upper end to a latch lever 35. This lever is pivotally secured at one end as at 36, to the standard 17, and its other end is formed as a wedge 37. In the periphery of the wheel 24 is a 5 channel 39 within which the wedge 37 is adapted to ride. The outer face of the bolt 27 extends substantially into the channel 39, and a transverse slot 42 in the bolt is adapted to be partially exposed within the channel 39 when the bolt is 10 in clutching position within the aperture 28 in the fly-wheel. The exposed wall of the slot 42 is formed with a bevel 43 adapted to be engaged by the wedge 37 which forces the bolt inwardly against the force of the spring 30, to withdraw 15 the bolt into the wheel 24, as seen in Fig. 10, and thus disengage the driving connection.

The relationship of parts is such that whenever the driving connection is interrupted as aforesaid, the ram will be in the uppermost or 20 open position. Thus, when the treadle 33 is depressed to withdraw the latch 35 from the channel 39, the bolt 27 will be released and will engage in one of the apertures 28, causing actuation of the ram. Ordinarily in a single stroke machine the 25 operator will release the treadle 33 immediately after the ram has begun to move, and the latch 35 will then automatically return to its position for engagement with the clutch bolt to halt operation of the machine upon completion of the 30 operating cycle.

The operating speed of the machine is ordinarily adjusted for a predetermined rate of movement of the ram 19 during a cycle of operation, and a period of short but perceptible duration will elapse between the moment when the clutch bolt 27 is released and the moment when the ram strikes the work. This interval is sufficient to allow slight shifting of the work on the bolster plate by a dexterous operator in order to 40 prevent spoilage of a work piece that may have been carelessly or hurriedly put in position; or will allow an insertion by quick movement of a work piece under the ram before the same strikes should the treadle 33 be prematurely depressed. 45 Such practice, however, eventually results in an accident whereby the operator is severely injured, and a salient feature of the present invention is the provision of safety mechanism for preventing this practice. In principle, the safety 50 mechanism is characterized by the provision of means requiring the use of both of the operator's hands during the time when the ram is in movement toward the bolster plate.

As herein shown, the safety device is in the 55 form of an attachment that may be secured to any press even after the same has been installed for operation. To this end, the mechanism of the device is supported principally upon a mounting plate 45 secured as by means of bolts 47 to the 60 standard 17 adjacent the clutch wheel 24 (Figs. 3 and 5).

Carried by the plate 45 is means adapted for operation with the clutch mechanism to withdraw the bolt 27 from engagement with the fly-wheel 65 22, this means being spaced only a partial revolution of the clutch wheel beyond the point where the latch 35 is adapted to engage the clutch bolt. As herein shown, a movable safety latch 48 is tangentially mounted relative to the clutch wheel 70 to normally engage at its inner end within the channel 39, a concavity 49 being formed on that part of the latch lying against the body of the clutch wheel. At its outer end the latch is pivotally secured in any suitable manner to the end 75

of a transverse lever arm 50. The inner end of the latch 48 is substantially offset to provide an angular shoulder 51 and a nose portion 52 having a beveled surface 53 adapted to engage with the bevel 43 in the wall of the slot 42 of the clutch bolt.

In the particular arrangement here shown by way of example, the safety latch 48 is maintained normally in what may be termed the active position, that is, with the beveled finger 52 located in the groove 39 of the clutch wheel, and with the concave portion 49 snugly contacting the body of the wheel. To this end, a rod 54 is pivotally connected at one end with the safety latch 48 through a boss 55 forming a part of or connected to the latch. This rod is slidably supported at its other end by means such as an eye bolt 57 and is closely surrounded by a coil spring 58, abutting at its forward end against a collar 59 rigid upon the rod. The eye bolt 57 is secured to the supporting plate 45 and forms an abutment for the rear end of the spring which bears against the collar 59 and thereby resiliently urges the rod 54 against the latch. The spacing of the safety latch 48 from the treadle operated latch 35 in the direction of movement of the clutch wheel is such that the ram will be halted a predetermined distance from the point of impact on the bolster plate. Therefore, the operator cannot possibly be injured by having his hand in the operative path of the ram.

For releasing the safety latch to resume operation of the press, I provide means which will necessitate the simultaneous use of both of the operator's hands. While this may take a variety of forms as circumstances or conditions require or warrant, I have shown a preferred practical releasing mechanism including a pair of substantially spaced similar handles 60 conveniently disposed for simultaneous manipulation by the operator and requiring him to use both hands removed a substantial distance from the operative path of the ram 19.

Each handle is connected by means such as a cable 62 with an opposite end of a transverse fulcrum lever bar 63, a stiff spring 64 being interposed between the end of the cable and the lever bar if desired to afford a resilient connection. At its center, the lever bar is pivotally connected to a goose neck arm 65, having at one end a bifurcated head 67 for receiving the bar, a pin 68 forming the pivotal connection. The other end of the arm 65 is rigid with the inner end of a transversely extending rod 69 fast at its outer end with one end of a lever 70. This lever is in loose engagement through the medium of a yoke 71 with the outer end of the rod 54 between the eye bolt 57 and a rigidly secured collar 72. Intermediate its ends, as at 73, the lever 70 is secured upon a fixed pivotal fulcrum 73 on the plate 45. Thus, when the handles are pulled, the cables 62 will draw the arm 65 and rod 69 forwardly, rocking the lever 70 which in turn draws the rod 54 to the right as seen in Figs. 3 and 5, against the pressure of the spring 58. This movement of the rod 54 draws the latch 48 toward the inactive position as seen in dotted outline in Fig. 3, and the clutch bolt will be released for operation. As soon as pressure is released on the handles 60, the spring 58 again forces the safety latch back to active position.

Due to the pivotal connection of the lever bar 63 with the arm 65, the bar will simply pivot when only one of the handles 60 is pulled. Simultaneously uniform pressure on both handles is

therefore required to operate the releasing mechanism, thereby insuring that both of the operator's hands will be occupied while the ram is in movement toward the impact point. Should the operator not uniformly and continuously depress the handles until the clutch wheel has been rotated to carry the clutch bolt beyond the point where the safety latch will engage the bolt, the ram will be halted. Moreover, the spacing of the ram from the bolster plate in its thus halted position will shorten the space remaining through which the ram must travel to the impact position to such an extent that the speed of the ram will carry it into the impact position before the operator can move a hand from either handle into the path of the ram. Manifestly, therefore, the operator's hands are fully protected from injury by the ram during operation.

If desired, an adjustable stop 74 may be secured near the end of each cable 62 for limiting the extent of separate or joint movement of the cables, suitable means being provided for engagement by the stops. In the present instance this means comprises rigid cable guide conduits 75 having their rear ends spaced a predetermined distance from the stops in the active position of the safety device. These conduits extend toward the front of the press and are suitably secured thereto as by means of brackets 77. If desired, the handles 60 may be hollow as best seen in Fig. 5, to slidably embrace the forward ends of the conduits. Through this arrangement the handles are always in a fixed position relative to other parts of the machine even when the press is tilted, and the operator must always uniformly pull both handles to effect a release of the safety device.

For halting the machine when declutched, and for preventing back-lash, the usual band type brake 78 may be utilized. When the brake is tight enough relative to the speed at which the press is being driven to halt the press substantially instantly, the apparatus is properly conditioned for operation. In such event, the position of the clutch bolt and safety latch will be as seen in Fig. 4, with the outer end of the bolt practically flush with the face of the clutch wheel, while the cam surfaces 43 and 53 are in abutment, and the finger 52 of the bolt extends only partially through the slot 42. It will be observed that the shoulder 50 is also substantially spaced from the side of the bolt. Such spaced relationship must normally be preserved in order to allow the inner edge of the shoulder to move through an arc as it is being moved to inactive position due to the tangential relation of the safety latch. In this relationship of parts the latch 48 is instantly responsive to manipulation to release the bolt.

However, should the brake 78 be too loose to exert sufficient force to stop the press substantially at once, the apparatus is not properly conditioned and may be dangerous. When this condition occurs the momentum of the machine will be sufficient to carry the clutch wheel beyond the normal stopping point when the bolt 27 is withdrawn, and the finger 52 of the safety latch will pass beyond the normal engagement point until the shoulder 51 abuts the side of the bolt as seen in Figs. 8 and 9. Preferably the pitch and length of the coacting cam surfaces 43 and 42 and the thickness of the finger 42 is such that when the finger 42 extends to its full extent into the slot 42 of the clutch bolt, the bolt will be withdrawn farther than usual into the bolt well 25. In this relationship of parts the inner edge of the shoul-

der 51 will be locked against the clutch bolt and thus prevent release of the safety latch until the clutch wheel has been reversed sufficiently to provide the spacing necessary to permit the shoulder to move through the arc it must describe in moving to release the bolt. The releasing force effected through manipulation of the handles 60 will be insufficient to overcome the weight of the ram and clutch wheel and cause the necessary reversal of the latter because the springs 64 will yield under the additional force necessary. Hence the operator will have to employ a suitable tool such as a crowbar sufficiently to reverse the clutch wheel; and to prevent a repetition of the locking action he must properly adjust the brake.

To absorb the shock against the safety latch when the apparatus is not properly conditioned and the shoulder 51 comes forcibly into locking engagement with the bolt, the lever arm 50 is pivotally connected to the supporting plate 45 as by means of a bolt 79 and cooperates with suitable shock absorbing means. In the present instance a shock absorber 80 provided with a strong spring 82 is connected to the supporting plate 45 in position to bear against the arm 50. Adjustment of the tension of the spring is possible through the medium of a bolt 83. The normal position of the lever arm 50 under compression is maintained by a stop pin 84.

Under differing operative requirements it may be desirable to halt the ram 19 at varying distances from the bolster plate 18. To this end, I provide a plurality of spaced bolt holes 85 in the plate 45 so that the position of the latch mechanism may be shifted by moving the pivotal bolt connection 79 as desired to provide the necessary adjustment. Thus, the safety latch may be moved to discontinue movement of the ram at the desired distance above the bolster plate.

Up to this point the machine has been described as being adapted for intermittent operation, that is, the ram being movable only at the will of the operator by releasing the safety mechanism. However, occasion may demand continuous operation of the ram as for blanking or die stamping, where the safety latch mechanism will not be necessary, but safety means to prevent the operator from placing his hand under the operating ram will nevertheless be desirable. To this end I have provided a removable cage guard 87 adapted to fit about a suitable die member 88 on the bolster plate 18 and of a height to prevent the operator from placing his hand under the ram regardless of the position of the latter. The ends of the guard are equipped with bayonet slots 89 adapting the guard ends to be removably received on bolts 90 suitably secured in the standard 17. Clamps 92 are secured to the handles 60 and rods 93 connect the clamps to the sides of the cage guard 87 for retaining the handles in the latch releasing position. Thus, the safety latch will remain inactive throughout the die stamping operation but possible injury to the operator will be prevented by the cage guard.

In operation, the fly-wheel 22 will be continuously driven, but the ram 19 will remain in the inactive position, as seen in Fig. 2, until the treadle 33 is depressed to release the latch 35 whereupon the clutch bolt 27 will engage with the fly-wheel to begin rotation of the crank 20 for operating the ram. However, the safety latch 43 will act immediately to withdraw the

clutch bolt from engagement with the fly-wheel, thus discontinuing further operation of the machine unless the operator has grasped and actuated both of the handles 60 to withdraw the safety latch to inactive position. Should the operator fail to actuate both handles 60 simultaneously, the ram will be instantly halted. Moreover, the point at which the ram will be halted by the safety mechanism and the speed of the ram when operating is such that it will reach the impact point before it would be possible for the operator to release his hold on either handle 60 and move his hand into the path of the ram should he be inclined to "beat" the ram for any purpose. As soon as either or both of the handles 60 are released, the safety latch returns to the position where it will again be active to halt movement of the ram after the treadle operated latch is released. Should the apparatus not be properly conditioned, the safety latch will lock with the clutch bolt and it will be necessary to reverse the clutch wheel to effect the release of the safety latch.

For continuous operation as in die stamping, the handles 60 will be depressed to retain the safety latch in the inactive position, and means such as the cage guard 87 will be utilized to prevent the operator from getting his hands under the ram.

Where the punch press is of such a character as to require the service of more than one operator, the safety apparatus may be provided with means requiring each operator to use both hands simultaneously to release the safety latch. Thus, a plurality of pairs of handles may be provided for operating the safety mechanism, so that each operator must utilize both of his hands simultaneously with every other operator in order to release the safety device and operate the machine.

From the foregoing, it will become evident that I have provided a novel safety device for punch presses that is simple and efficient in operation, is sturdily and simply constructed, and is adapted for a variety of conditions.

I claim as my invention:

1. In a machine of the character described, a reciprocable impact element operable through a given working cycle including substantial movement from an initial position to an impact position, a prime mover for driving said impact element at a predetermined speed, selectively operable connecting means including a driven member intermediate said prime mover and said impact element, means normally acting to effect a driving connection between said driven member and the prime mover, and control means requiring the simultaneous use of both of the operator's hands for operating said connecting means and arranged normally to release said driving connection to halt operation of the machine if the operator removes either hand before said impact member has moved beyond a given intermediate position between said initial and impact positions whereafter the speed of the impact element will carry the latter from said intermediate position to impact position before the operator can move a hand from said control means into the path of the element.

2. In a punch press, the combination of a power driven impact element reciprocable through a working stroke of predetermined length, a prime mover for driving said ram at a predetermined speed, clutch mechanism for

operatively connecting said prime mover and impact element, control means adapted for intermittently operating said clutch and including an actuator movable by the physical effort 5 of an attendant operator, and additional manually operable safety means requiring the simultaneous use of both of the operator's hands adapted to act with said clutch to discontinue operation of said impact element after said control means has been operated if the operator releases either hand before said impact element 10 has moved to within a predetermined distance from the impact point, said distance being such that said impact element will reach the impact 15 point before the operator can move a hand into its path.

3. A machine having a movable part, a prime mover for actuating said part through a predetermined movement cycle, intermediary means 20 including a clutch bolt acting with said prime mover for selectively engaging the same to actuate said movable part, control means including a control member normally active to discontinue engagement between said prime mover and clutch bolt, and means requiring the use of both hands 25 of the operator for moving said control member to inactive position placed at such a point relative to said movable part that said control means will operate to discontinue engagement between 30 said prime mover and clutch bolt to halt movement of said movable part more quickly than the operator can move his hand from said releasing means to a position in the path of said movable part.

35 4. In a machine of the class described, a movable part having a predetermined operative movement cycle, a prime mover for actuating said part, clutch means including a bolt for selectively engaging said prime mover to actuate 40 said movable part, control means including a latch adapted to discontinue engagement between said bolt and said prime mover, manual means operable only when manipulated by both 45 hands of the operator for rendering said latch inactive, and means for adjusting the position of said latch for varying the point at which said latch becomes active.

5. In a punch press including a power driven ram, operating means including an actuator 50 movable at will conveniently disposed for actuation by the operator, clutch mechanism responsive to said operating means, safety mechanism auxiliary to said operating means active to discontinue operation of said clutch mechanism 55 after said operating means has been actuated by the operator, and manual means independent of said actuator including a plurality of substantially separated members for rendering inactive said safety mechanism only when all of said 60 members are actuated simultaneously.

6. In a machine of the character described, a movable part, a prime mover for actuating said part through a predetermined movement cycle, intermediary means acting with said prime 65 mover for selectively engaging the same to actuate said movable part, control means including a control member adapted to discontinue engagement between said prime mover and intermediary means, operating means for moving said control member to inactive position, adjustable means for properly conditioning said movable part to halt 70 instantaneously when said intermediary means is disengaged by said control member, and means operative with said control member adapted to lock said control member against 75

movement by said operating means unless said movable part is properly conditioned.

7. In a machine of the character described, a movable part, a prime mover for actuating said part through a predetermined movement cycle, 5 intermediary means including a reciprocable element selectively engageable with said prime mover to actuate said movable part, control means including a control member adapted to discontinue engagement between said prime 10 mover and reciprocable element, resiliently connected operating means for moving said control member to inactive position, an adjustable brake for properly conditioning the machine to halt movement of said movable part substantially instantaneously when said reciprocable element is disengaged from said prime mover by said control member, and means on said control member cooperative with said reciprocable element due to momentum of said movable part when said brake 15 is out of adjustment to lock said control member against movement to inactive position by said operating means.

8. In a power operated punch press including a ram, a prime mover, a clutch including a reciprocable element engageable with said prime mover for actuating said ram, control means including a control member adapted to discontinue engagement between said prime mover and said reciprocable element, manipulable means for releasing and moving said control member to inactive position, an adjustable friction brake tensioned to halt instantaneously movement of said ram when said reciprocable element is disengaged 25 from said prime mover, and means on said control member engageable in active position with said reciprocable element for locking said control member against release by said manipulable means when said brake is out of adjustment and its tension is insufficient to instantaneously halt 30 the ram.

9. In apparatus of the character described, a movable part, a prime mover for actuating said part through a predetermined movement cycle, intermediary means acting with said prime mover 45 for selectively engaging the same to actuate said movable part, control means including a control member adapted intermittently to discontinue engagement between said prime mover and intermediary means, manually operable means for 50 releasing and rendering said control member inactive, and non-manual means cooperative with said manually operable means for holding the latter in releasing position for maintaining said control member continuously inactive to allow 55 continuous operation of said movable part.

10. In apparatus of the character described, a movable part, a prime mover for actuating said part through a predetermined movement cycle, clutch mechanism between said prime mover and 60 said movable part and including a member selectively engageable with said prime mover, control means including a principal latch adapted to discontinue engagement of said member with said prime mover, means operable to release said 65 latch and allow engagement of said clutch member with said prime mover, an auxiliary latch spaced from said principal latch and arranged for engagement with said member to disengage the same from said prime mover immediately following release of said principal latch and before said movable part has traveled beyond a predetermined point, means for urging said auxiliary latch into active position, and manually operable means including a pair of spaced members op- 70 75

erable to overcome said urging means for rendering said auxiliary latch inactive and arranged to require substantially equal and simultaneous manipulation for operation.

5 11. In apparatus of the character described, a movable part, a prime mover for actuating said part through a predetermined movement cycle, intermediary means acting with said prime mover for selectively engaging the same to actuate said movable part, control means including a control member adapted intermittently to discontinue engagement between said prime mover and intermediary means, handles hanging from the upper part of the apparatus and operatively connected with said control member for releasing and rendering the same inactive, and means adapted to be connected to said handles for holding the latter in releasing position for maintaining said control member constantly inactive to allow continuous operation of said movable part.

10 12. In apparatus of the character described, a reciprocating ram, a prime mover for actuating said ram through a predetermined movement cycle, intermediary means acting with said prime mover for selectively engaging the same to actuate said ram, control means including a control member adapted intermittently to discontinue engagement between said prime mover and intermediary means, manually operable means for releasing and rendering said control member inactive, and safety means for entirely preventing lateral movement of the operator's hands into the path of said ram including members extending into engagement with and connected to said 15 manually operable means for holding the latter in releasing position for maintaining said control member constantly inactive to allow continuous operation of said ram.

15 13. In apparatus of the character described, a safety device comprising an auxiliary unit adapted for attachment to a power driven machine already installed for operation and having intermittently operable clutch mechanism for actuating the machine through a given working cycle, said device including a mounting member for attachment to the machine, a clutch actuator carried by said member and normally operable promptly after the machine has been set into operation to render the clutch inactive and halt further movement of the machine, and manually operable means requiring the simultaneous use of both of the operator's hands connected with said actuator for rendering said actuator inactive.

20 14. In a power driven punch press, in combination, a ram having a working stroke of predetermined length, a prime mover for driving said ram at a predetermined speed, connecting means including a part normally operable to effect a driving connection between said prime mover and said ram, and control mechanism having means normally active to coact with said part to maintain the latter against operation and embodying manually operable means requiring simultaneous use of both of the operator's hands for rendering the normally active means inactive, said control mechanism being arranged to halt said ram at an intermediate position of its working stroke unless both hands of the operator are simultaneously occupied in operating said

25 mechanism, said intermediate position of the ram being in predetermined spaced relation to the end of its working stroke whereby the speed at which said ram is driven will carry it from said point to the end of its working stroke before the operator can move a hand from said manually operable means into the path of the ram.

30 15. In a power press or like machine embodying an impact element and driving means for moving said element through a given operating cycle including initial and impact positions, a rotatable member including selectively movable means for connecting the same with said driving means and having a driving connection with said impact element, control means arranged to engage and to force said movable means to inoperative position when said element has reached initial position in its operating cycle, and safety means supplemental to said control means requiring simultaneous use of both hands of the 35 operator and having a part normally in a position spaced from said control means in the direction of movement of the driving means for engaging and rendering said movable means inoperative shortly after the latter has been released by said control means unless both hands of the operator are simultaneously in use to maintain said part inoperative.

40 16. In a power press or like machine including an impact element and driving means for moving said element through a given operating cycle, connecting means intermediate said element and said driving means for effecting a driving connection therebetween and having selectively operable controlling means active at one point in said operating cycle to engage said connecting means to discontinue said driving connection, safety means requiring simultaneous use of both hands of the operator effective after said element has commenced to move toward impact and at a point spaced from said controlling means in the direction of movement of said driving means to engage said connecting means to discontinue the driving connection after it has been reestablished unless both hands of the operator are in use as required aforesaid, and means coactive with said safety means for absorbing any shock thereon incident to the momentum of said element.

45 17. In combination in a machine having an element adapted for intermittent actuation through a predetermined movement cycle from an initial position to an operative position and return to initial position, continuously running driving means, means providing a driving connection between said element and said driving means and including a clutch biased for movement to effect said driving connection automatically, means for declutching said driving connection in said initial position of said element and being operable at will to permit resumed operation of the clutch, and auxiliary safety mechanism independent of said last mentioned means operable after said driving connection has been completed by the resumed operation of said clutch to declutch the same again and being arranged to maintain said element positively against movement toward said operative position.
